UNITED STATES PATENT OFFICE.

JOHN WILLIAM WEBB, OF ATHENS, GEORGIA.

SEAL AND BRACE FOR BOXES.

1,364,225.

Specification of Letters Patent.

Patented Jan. 4, 1921.

Application filed March 13, 1916. Serial No. 83,843.

To all whom it may concern:

Be it known that I, JOHN W. WEBB, a citizen of the United States, residing at Athens, in the county of Clarke and State of Georgia, have invented certain new and useful Improvements in Seals and Braces for Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to means for sealing the flaps of boxes or cartons and for strengthening the corners of the boxes. It has for its object to provide sealing and strengthening means prepared for ready application by the merchant in his place of business where the box flaps are closed and sealed in the operation of filling the box or carton in readiness for shipment or storage. Heretofore the flaps have been sealed by applying a coating of glue or like adhesive substance to the meeting surfaces of the flaps. An objection to such method is that through carelessness of the operator or workman the adhesive substance has been 25 imperfectly applied, either covering only a portion of the surface, or more thickly applied at one point than another, or applied in an imperfect condition as to consistency or fluidity, so that the sealing has been defective and the necessary strength for security not obtained. In other instances, the flaps have been sealed by applying strips of tape to portions of the box in manufacturing the box so that when the boxes have been 30 filled and the flaps folded an adhesive may be applied to the remaining exposed face of the tape to cause the folded flap to be secured. An objection to such method is that the adhesive may be imperfectly applied so 35 that a defective sealing is effected; and furthermore the tapes are applied in the manufacture of the boxes and not capable of application by the merchant to whatever type or make of boxes he may use in his business.

40 Another method is to apply tapes to the outside of the boxes and across the folded flaps but this method is open to the objection that the meeting faces or surfaces of the flap are not held or sealed one to the other, and the 45 tapes do not furnish the strength of security

to meet all conditions of handling the boxes in shipment.

To provide sealing and strengthening means obviating the objection mentioned and affording the maximum of security and 50 strength and capable of application by the merchant in his place of business during the operation of filling and sealing the boxes or cartons, the invention consists in the features hereinafter particularly described and 55 then sought to be clearly defined by the claims, reference being had to the accompanying drawings forming a part hereof, and in which—

Figure 1 is a perspective of a box or carton having the invention applied and indicating the method of applying the tapes;

Fig. 2 is a perspective of one corner of a box showing the flaps folded, and a corner brace at one stage of its folding;

Fig. 3 a similar view showing another stage of folding the corner brace;

Fig. 4 a perspective of a sealing tape, both faces of which are provided with the adhesive;

Fig. 5 a perspective of a corner brace, with one gummed face, as it appears before its attachment to the double face gummed tape;

Fig. 6 a perspective of the double face 85 gummed tape, and corner braces attached, with the ungummed face of the corner braces exposed;

Fig. 7 is a view similar to Fig. 6, looking from the opposite side of the double face 90 gummed tape and corner braces, and with the double faced tape wider than shown in Fig. 6;

Fig. 8 is a perspective of a portion of a box or carton, having the tape and corner 95 braces of Fig. 7 applied, and showing position of corner braces before the box outside flaps are folded;

Fig. 9 is a vertical section through a sealed box on the line 9—9 of Fig. 10;

Fig. 10 is a vertical section through a box on the line 10—10 of Fig. 9.

In the drawings the numeral 1 designates a box or carton of a usual type, formed of fiberboard or pulpboard, or double faced 105 corrugated strawboard, and having opposite open ends, each provided with folding end flaps 2 and folding side flaps 3.

The numeral 4 designates a strip or tape of paper or fabric, in length and width suit- 110

able to the dimensions of the box or carton with which it is to be used, and having both faces gummed with a suitable adhesive substance 5 which when moistened will adhere 5 to the contiguous surfaces of the flaps which it is designed to securely seal or hold together. As illustrated the double face gummed tape is interposed between the flaps 2 and 3, being first moistened on both sides 10 and then laid upon the inner folded flaps 2, along the edges of the ends of the box and then the outer flaps 3 are folded upon the tapes, and thus the tapes with their moistened opposite gummed faces in contact with 15 the outer surfaces of the inner folded end flaps and the inner surfaces of the outer folded side flaps are caused to hold the contiguous faces of the two sets of flaps together in intimate union throughout the entire area of the double faced gummed tape. The tapes being prepared with their two faces normally gummed and not moistened until to be applied in sealing the flaps both faces are brought to the same degree of adhesive 25 ness at the moment that the flaps are to be sealed one to the other by being pressed together and the same conditions will prevail on both faces of the tape at the time that the flaps are thus to be secured together, 30 with the result of a closer union between the contiguous faces of the flaps uniformly throughout the entire area of the tape than would be the case if the tape were applied to one flap in the making of the box and an adhesive applied to the other face when the other flap is to be secured thereto. The tape, with both faces normally gummed, and moistened on both faces at the time the flaps are to be sealed, is given a degree of 35 flexibility or pliability that makes it possible for both surfaces to conform to the contiguous surfaces of the flaps at the time that pressure is applied to join the flaps together, and thus also a closer union between 40 the flaps is obtained and the two, along the line of union, are made practically integral or one. These are some of the advantages derived by forming the tape with two normally gummed faces, beside the advantage 45 of enabling the merchant to use the sealing means with whatever type or make of box he may for the time be using.

The double face gummed tape 4 may be the full width of the inner folding flaps 2 55 as indicated in Fig. 8 of the drawing, or may be narrower as illustrated in Fig. 1. If narrower, additional double face gummed tapes 6 may be applied along or near the inner edges of the flaps 2 as illustrated in 60 Fig. 1 of the drawing. The advantage of having the double face gummed tape along the inner edge of the flaps 2 is that being back from the fold or connection between the flaps and the walls of the box it affords 65 greater leverage or resistance to the tend-

ency to force the flaps outwardly when the box strikes along the edges in handling, and thus contributes to the strength of the box.

For the purpose of giving additional strength to the box, particularly at the corners where the greatest liability to split or break occurs, I provide corner braces which are gummed only on one face so that the exposed faces will not present a gummed surface, the braces being so formed that a portion thereof will lie between the folded flaps and the other portions will lie outside the box and lap or cover the walls at the corners and also the corner portions of the outside folded flaps thereby strengthening the box 80 at the corners and also contributing to still more securely hold or seal the outside flaps. These corner braces are designated by the numeral 7. The brace is made of paper or fabric and provided on one face with a suitable adhesive substance 8. It is slotted diagonally from one corner as indicated at 9 so as to form a tongue 10 that may lie between the flaps 2 and 3 at a corner of the box, two members 11 and 12 to lie against the walls of the box, a third member 13 to lie upon the outer folded flap 3, and a tongue 14 to extend over the edge of the folded flap and overlie the member 11 so as to effectively shield and seal the corner of the 95 box. These braces may be formed and applied separately from the double face gummed tape, or may be attached to the ends thereof so as to be a part thereof. In applying the corner braces, the tongue 10 100 thereof is preferably caused to lie underneath the double face gummed tape 4; the portion 11 is then pressed down against the outside of the end wall of the box, as shown in Fig. 1; the portion 12 is then pressed 105 against the outside of the side wall as shown in Fig. 2; the outer folding flap is closed and the portion 13 of the brace then pressed down on the top of the flap as shown in Fig. 3; and then the tongue 14 is pressed down on the end wall and over the portion 11, and thus the seal is effected, the moistened gummed face of the brace causing the several portions of the brace to securely adhere to the surfaces with which they come in 115 contact. The corner braces and double face gummed tape may be formed together as shown in Fig. 6 before being applied to the box, or they may be formed and applied separately, the tongue 10 of the corner brace 120 being caused to adhere to the inner folded end flap, and the double faced tape then applied, and the other portions of the brace affixed as previously described; or under some conditions, if so desired, only the 125 double face gummed tape may be used, or only the corner braces. It is preferred however to use together the double face gummed tape and the corner braces as in that case they coöperate to effect a more secure hold- 130

ing together of the several parts and contribute to produce a much stronger box.

By providing sealing and strengthening means adapted for application by the merchant in his place of business during the operation of filling and sealing the cartons or boxes, the means is applicable to whatever type of box may be used by the merchant, and a more efficient sealing of the box is obtainable because of the conditions previously enumerated. Furthermore, a fiberboard, pulpboard, or double faced corrugated strawboard box meeting the various requirements of the railroad transportation and express companies, as to sealing and strain resisting qualities, is provided and at less expense than under other means employed with the view of meeting such requirements; and the box is made materially stronger and with greater strain resisting qualities at points where heretofore they have been the weakest, that is, at the flaps and the corners. These advantages are due in a large measure to the fact that the sealing tape employed is formed with two normally gummed faces so that when the tape is dipped in a moistening liquid the tape is rendered more pliable and both surfaces are put in the same condition so that when the tape is laid between the box flaps the contiguous surfaces of the outer and inner flaps are secured one to the other throughout the whole area of the tape at both faces thereof and under uniform conditions of adhesive- ness so that a more efficient and secure sealing with added strength is obtained.

I have illustrated and described the best mode of applying the invention at present known to me and as demonstrated by various tests but changes may be made in the details without departing from the essentials as specified in the appended claims. It is also obvious that where the width of the box makes it necessary, or desirable, the double faced tape may be made up of separate sections or lengths brought together to make practically a continuous length, each section at the corners being provided with a corner brace.

Having described my invention and set forth its merits what I claim is:

1. In boxes having folding closure flaps, means for securing the flaps in closed position and bracing the corners of the box, consisting of a tape having its opposite faces gummed for adhesion to contiguous faces of inner and outer flaps of the box and end corner braces having a gummed surface formed to lap on the adjacent walls of the box at the corners and onto the exposed face of an outer folded flap and having a tongue to fold over the edges of the folded flap and wall of the box and onto the wall adjacent to said edges, the corner braces being rectangular shaped and cut along a diagonal toward the center. 55 60 65

2. In boxes having folding closure flaps, means for bracing the corners of the box consisting of a gummed faced member formed to lap on the adjacent walls of the box at the corners and onto the exposed face of an outer folded flap and having a tongue to fold over the edges of the folded flap and wall of the box and onto the wall adjacent to said edges, said corner member being rectangular shaped and cut along a diagonal 70 75 toward the center.

3. In boxes having folding closure flaps, means for securing the flaps in closed position and bracing the corners of the box, consisting of a double face gummed tape for adhesion to the contiguous faces of folded flaps, and corner braces having a gummed face and formed to lap on the walls of the box at the corners and onto the exposed face 80 85 of an outer folded flap and having a tongue to fold over the edges of the folded flap and wall of the box and onto the wall adjacent to said edges and a tongue to lie between the folded flaps and in contact with the tape, 90 said corner braces being rectangular shaped and cut along a diagonal toward the center.

In testimony whereof I affix my signature in presence of two witnesses.

JOHN WILLIAM WEBB
